UNITED STATES PATENT OFFICE

2,456,008

MUSICAL INSTRUMENT

John W. McBride, Burbank, Calif.

Original application May 29, 1942, Serial No. 444,963. Divided and this application December 3, 1945, Serial No. 632,410

26 Claims. (Cl. 84—320)

1

This invention relates to a musical instrument, and more particularly to a stringed instrument in which the strings are set into vibration by mechanical means. This application is a continuation of my abandoned application filed on May 29, 1942 under Serial No. 444,963 and bearing the same title.

It is one of the objects of this invention to provide such an instrument, utilizing a mechanical means, such as a percussion device, and having strings the free lengths of vibration of which are adjustable.

It is another object of this invention to make it possible to use the fingers of either hand, or any combination of the fingers of both hands, for determining the free lengths of selected strings, and to operate the mechanism for setting selected strings into vibration by appropriate manipulation of one or both lower extremities of the body.

It is still another object of this invention to provide a simple form of mechanism by the aid of which the vibration of the strings is effected by the lower extremities; and particularly to provide a system thus operated that selects the combination of strings to be vibrated.

It is still another object of this invention to provide a mechanism operable by the lower extremities for selecting and vibrating the strings, and constructed in such manner that the rate of angular movement of the mechanism determines the rate at which successive impulses are imparted to the strings.

It is still another object of this invention to make it possible to impart impulses to the selected strings in such manner that impulses are imparted to the strings in succession, rather than simultaneously; and, in this connection, the period intervening between impulses imparted to successive strings may be determined by the operator, as, for example, by the rate of angular movement of the selector mechanism.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

Referring to the drawings:

2

Figure 1 is a front elevation of an instrument incorporating the invention;

Fig. 2 is a vertical section taken along plane 2—2 of Fig. 1, some of the elements being shown in diagrammatic form;

Fig. 3 is a fragmentary top plan view of the instrument;

Fig. 4 is an enlarged fragmentary longitudinal sectional view illustrating the selector mechanism;

Figs. 5, 6 and 7 are fragmentary sectional views, taken generally along correspondingly numbered planes of Fig. 4;

Figs. 8 and 9 are enlarged sectional views, taken respectively along planes 8—8 and 9—9 of Fig. 2;

Figs. 10 and 11 are enlarged fragmentary sectional views taken along correspondingly numbered planes of Fig. 9;

Fig. 12 is a fragmentary sectional view, taken along plane 12—12 of Fig. 8;

Fig. 13 is a fragmentary sectional view, taken along section 13—13 of Fig. 9;

Fig. 14 is a view, mainly in section, of the selector mechanism utilized in connection with the invention;

Figs. 15 and 16 are views similar to Fig. 14, but illustrating different positions of the selector mechanism;

Fig. 17 is a fragmentary enlarged section of a part of the selector mechanism illustrated in Figs. 4 and 5;

Figs. 18 and 19 are fragmentary sectional views taken along correspondingly numbered planes of Fig. 17; and

Fig. 20 is a fragmentary views of a portion of the apparatus illustrated in Fig. 17.

The instrument in general includes a table-like structure 1 (Figs. 1, 2, 3 and 4). As shown most clearly in Fig. 2, this table-like structure is supported by a pair of side walls 2 and a front wall 3 (see also Figs. 4, 5 and 7). The rear of the structure is open to accommodate the lower extremities 4 (Fig. 2) of the player underneath the table 1, for manipulation of a vibrator mechanism

hereinafter to be described in detail. The front wall 3 may be provided, if desired, with a sound reproducer or loud speaker mechanism 5. This loud speaker may be so connected electrically with the musical instrument as properly to amplify the sound impulses produced by playing the instrument.

The player is seated by the table 1, and in a comfortable position, so that the lower extremities may take the position illustrated in Fig. 2. His upper extremities may both be utilized for the

purpose of adjusting the free vibrating length of a number of tensioned strings supported by the aid of the table 1. In the present instance eight such strings are indicated (Figs. 2 and 3.) These eight strings in the present instance are shown as comprising two sets of four strings each, the strings of one set alternating with the strings of the other set.

Thus, for example, as shown most clearly in Figs. 3, 5, 10, 12, and 13, one set of strings may comprise the strings 6, 7, 8 and 9.

The apparatus for adjusting the length of this first set of strings is quite similar to that disclosed in a prior application filed in the name of John W. McBride, Serial No. 388,379, filed on April 14, 1941, for "Stringed musical instrument," now Patent No. 2,316,799, granted April 20, 1943.

The second set of tensioned strings comprises strings 10, 11, 12 and 13 (Figs. 2, 3, 5, 9, 10, 11 and 13). The mechanism for adjusting the free lengths of this second set of strings is quite similar to that disclosed in still another application filed in the name of John W. McBride, Serial No. 434,855, filed on March 16, 1942, for "Stringed musical instrument," now Patent No. 2,368,256, granted January 30, 1945.

While the disclosures of these two prior applications have been substantially embodied herein, any other suitable mechanism for adjusting the free lengths of vibrations may be utilized.

The first set of strings 6, 7, 8 and 9 is so arranged that each of these strings is anchored adjacent the right hand end of the instrument as viewed in Fig. 3. At the opposite ends of these strings, means are provided for tuning, as by the tuning keys 18.

Thus, for example, as shown most clearly in Fig. 8, string 9, representative of all of the strings of the first set, is shown as having a knotted right hand end 19 adapted to engage in a keyhole slot 20. This keyhole slot 20 is provided in the upper wall 21 of the stationary frame 22, which has a lower wall 23 (Fig. 11). The manner in which the frame 22 is supported in the table 1 will be described hereinafter. The string 9 passes over the bottom of a notch 24 formed in the upright wall 25 of the frame 22. At its left hand end the string 9 passes over a felt damper pad 26 (Figs. 8 and 12). This damper pad 26 is disposed in a recess 27 formed in the upright wall 28 of a frame structure 29. This frame structure 29 rests at its lower surface in an appropriate recess in the table 1 (Fig. 8). It is held in place as by the aid of the flange 30 which accommodates the fastening screws 31. The left hand wall 32 of the frame 29 is provided with a series of notches 33 for the strings 6, 7, 8 and 9. The string 9 passes over one of these notches and on to a tuning peg 34, accommodated in an appropriate aperture in the table 1. The tuning peg 34, together with the tuning pegs of all of the other strings in the first set, may be operated by the keys 18 heretofore mentioned and illustrated in Figs. 1 and 3.

In order to adjust the free length of vibration of any of the strings 6, 7, 8 and 9, use is made of a series of rotatable helically crested rods 14, 15, 16 and 17 (Figs. 8, 10 and 12). These rods, as described in the earlier of the two hereinbefore mentioned prior filed applications, are arranged for rotation immediately below the respective string. Thus, the crested rod 17 is shown as having an axis of rotation immediately below the string 9 and substantially parallel therewith. This rod 17 is shown as rotatably supported at its right hand end by the aid of the

reduced shaft portion 35. This shaft portion is rotatably journaled in the bracket member 36, supported in an appropriate depression in the top of the table 1 and having a vertically extending leg (see also Fig. 3). This vertical leg is placed adjacent the vertical wall 37 defining the right hand end of the recess 38 formed in the top 1.

The left hand end of the crested rod 17 is provided with a similar shaft portion 39 (Fig. 8) journaled in the vertical wall 32 of the frame 29. This rod, as shown most clearly in Figs. 8 and 12, is cylindrical between the walls 32 and 28; but the crest 40 of the rod 17 ends quite closely to the right hand side of the wall 28. The wall 28 may be slotted, as indicated in Fig. 12, to permit the free passage of the rod 17.

As explained in the earlier of the two prior applications hereinbefore identified, the angular position of the rod 17 determines which point of the helical-like crest 40 is in contact with the string 9, and accordingly determines its free vibrating length. For rotating these rods 14, 15, 16 and 17 to any desired extent to adjust the length of the corresponding string, use is made of a plurality of keys 40', 41, 42 and 43 (Figs. 3, 8 and 12). These keys each have an upper portion in sliding contact with the lower surface of a protector plate 44. A lower portion of each of the keys slides in a dovetail slide provided in the bottom 30 of the frame 29. The dovetail may be formed for example by a plurality of strips 46, 47, 48, 49 and 50. These strips have edges overlapping the lower portions 45 of the keys. These keys have ends 51 strengthened as by the ribs 52, and capable of being manipulated by the fingers of the player.

A downward depression of any one of the keys 40, 41, 42, 43, as viewed in Fig. 3, or a motion toward the right, as viewed in Fig. 12, will cause 40 a corresponding rod 14, 15, 16, or 17 to be rotated in a counterclockwise direction. Motion of the keys may be transmitted to the rods by the aid of a spiral spring disposed over the cylindrical left hand portions of the rods. For example, rod 45 16, with which key 42 is associated, is provided with a spiral spring 52. The inner end of the spiral spring is anchored in a keyway 53 of the rod 16. The outer end 54 is anchored in a slot 55 formed in the bottom portion 45 of the key 42. As the key 42 is pushed inwardly, or toward the right as viewed in Fig. 12, the spring 52 is unwound and rod 16 is rotated. The degree of unwinding is determined by the position of the key 42. Release of the key will permit the spiral 55 spring 52 to wind up on the rod 16 and to urge the key 42 back to its starting position.

The starting position is limited as by the bottom wall of the frame 29. For this purpose, frame 29 has a slot 57 (Fig. 12) into which stop pin 56 extends. This pin is carried by the lower side of key 45 and contacts the left hand wall of slot 57 when the manipulation of key 45 ends. A similar key mechanism is provided for each of the rods 14, 15, 16, and 17.

65 These key mechanisms are produced by the cover member 44 which may be conveniently hinged, as indicated at 58 (Figs. 3 and 12), to a hinge plate 59 disposed on one edge of the table 1. Conveniently, the inner edge 60 (Fig. 3) of the 70 protecting cover 44 may cooperate with graduations, such as 61, marked on the upper surface of the keys. These graduations thus serve as an indication of the angular position attained by the corresponding helically crested rod and, accordingly, the pitch of the corresponding string.

When the keys 40', 41, 42, and 43 are in their outermost positions, and stop pins 56 are active against the left hand end of the slots 57, the free length of the corresponding string is determined by the left hand ends of the crests. As shown most clearly in Fig. 3, these crests, in this free position, engage the strings quite close to the end wall 28 of frame 29.

As shown most clearly in Fig. 8, the cover plate 44 projects over the pegs 39. At its right hand edge it may be provided with a series of downwardly depending ears 62. It may also be provided with an ornamental apex 63. This cover or protector plate may of course be swung about the hinge 58 to gain access to the key mechanism and to the strings. This is necessary in the event of replacement or repair of the strings or any of the associated parts. The protecting cover forms a convenient rest for the left hand of the player in the process of manipulation of the keys 40', 41, 42 and 43.

The electrical pickup to transform the vibrations of the string into electrical vibrations so that they may be utilized in connection with the loud speaker 5 is indicated in diagrammatic fashion by the rectangles 64 in Fig. 3. These rectangles are intended to represent the pickup mechanism supported in the table 1 and disposed respectively under the strings 6, 7, 8 and 9.

Control of the electrical circuits utilized in connection with the electrical pick-up is provided by the aid of a pivoted lever 65 (Figs. 3 and 12). This pivoted lever is provided with an appropriate head or handle 66 arranged at the right of the key 43 for convenient manipulation by the thumb of the player. It is shown in Fig. 12 as pivoted in a post 67 supported in any appropriate manner in the bottom wall of the table 1. A recess 68 is provided for its accommodation. The lever 65 is shown as provided with a plurality of spring contacts 69 forming circuit controllers in conjunction with a stationary portion 70 of the mechanism. These circuit controllers, comprising the spring fingers 69 and the member 70, may provide variable resistors or other impedances adapted to be adjusted by appropriate manipulation of the head or handle 66.

In order to permit freedom of movement of the fingers of the player, the table 1 may be provided with a recess 71 (Fig. 3) beneath and around the outer ends of the keys 40', 41, 42, 43 and the lever 65.

The second set of strings 10, 11, 12 and 13, alternating with the first set of strings is so arranged that the free length of these strings may be adjusted by the right hand of the player. The left hand ends of the strings in the second set are anchored in the wall 28 of frame 29 (Figs. 9 and 12). For this purpose the wall 28 is shown as provided with the keyhole slots 72, receiving the knotted ends of the strings. Furthermore, the upper edge of the wall 28 is notched for the accommodation of these strings.

The right hand ends of these strings pass over the felt damping pads 73 disposed on the top wall 21 of the frame 22 (Figs. 9, 11 and 13). The left hand wall 25 of frame 22 is provided with appropriate recesses as clearly indicated in Fig. 13, for accommodation of these damping pads. The rear wall 74 (Figs. 9 and 11) is provided with appropriate notches such as 74' over the bottom of which the strings 10, 11, 12 and 13 respectively pass. The right hand ends of the strings are each wound around a tuning peg such as 75 (Fig. 9).

The tuning pegs may be turned as by the aid of the keys 76 illustrated in Fig. 3.

Projecting from the rear of the frame 22 is a narrow flange 77. By the aid of this flange the frame 22 may be attached to the top of the table. The right hand wall 74 projects downwardly against a wall 78 forming one end of the recess 79 formed underneath the strings of the second set (Figs. 2, 9 and 11).

10 The mechanism for adjusting the free length of each of the second set of strings 10, 11, 12 and 13 can be explained most clearly in connection with Figs. 9, 10, 11 and 13. This mechanism is quite similar to that disclosed in the later of the 15 two prior filed applications hereinbefore identified.

The mechanism associated with string 13 and illustrated in Fig. 9, is illustrative of the mechanism for all of the other strings. Therefore the 20 description of the mechanism for this string will serve as a description for all of them.

Disposed immediately below the string 13 is a series of movable frets 80, any one or pair of which may be urged into contact with the lower 25 end of the string 13. These frets are in the form of rectangular bars arranged transversely to the string (Fig. 3). They are guided for movement toward and away from the string 13 by the aid of a channel guide 81, there being one such guide 30 associated with each string. This channel guide, as shown most clearly in Figs. 9, 10 and 13, has depending flanges and a lower guide member 82. A series of screws, such as 83, serves to hold parts 81 and 82 together. Furthermore, the guide 35 member 81 has a projecting portion 84 (Fig. 9) which extends beneath the upper wall 21 of frame 22. Through these overlapping edges may be passed fastening means, such as the screws 85. At the left hand end the guide 81 is attached to the table 1 as by the aid of the projection 86 40 which is received in a shallow recess in the top of the table.

Each of the frets 80 is urged, as by a compression spring 87, in a direction away from the string 45 13. These compression springs are disposed around a corresponding fret 80. Its upper end abuts the lower surface of the guide 81. Its lower end acts upon a pin 88 passing transversely through the fret 80.

50 Movement of a selected fret or pair of frets to determine the free length of the string 13 is accomplished by the aid of a rotatable rod 89 disposed beneath the guide 82 and having an axis of rotation substantially parallel with the string 13. This rod 89 is provided at its right hand end with a short shaft 90 (Fig. 9) journaled in the wall 74, At its left hand end the rod 89 is provided with similar shaft 91 journaled in a bearing member 92 fastened to the bottom side of the cover 82.

55 In addition, one or more intermediate bearings may be provided for all of the rods 89. For example, a bearing member 93 (Figs. 9 and 10) may be fastened to the guide 81-82 so as to depend therefrom. This bearing member 93 extends across all of the rods 89 and is provided with half round recesses for the accommodation of the reduced portions 94 of the rods 89. A cap member 95 is fastened over this bearing member 93 to complete the bearing mechanism.

60 The frets 80 project downwardly beyond the cover member 82. They are each provided with a pointed cam follower projection 96. Cooperating with these projections are a series of cams 97. 65 These cams are carried by the rod 89 and are

angularly displaced to form a general helical-like arrangement. As explained in the specification of one of the prior filed applications, these cams may be brought into action in succession to operate any pair of frets 80. This is accomplished by appropriate angular adjustment of the rod 89.

Angular movement of the rod 89 and the other three rods associated with the other three strings 10, 11 and 12, is accomplished by appropriate manipulation of the keys 98, 99, 100 and 101. These keys are arranged at the right hand end of the instrument as viewed in Fig. 3 and are quite similar to the keys 40', 41, 42 and 43. They are intended to be manipulated by the fingers of the right hand of the player.

Key 101 operating the rod 89 corresponding to string 13 is guided for movement transverse to the strings, by the aid of a recess formed in the lower wall 23 of the frame 22. The key is held in this recess as by the aid of the strips 102 and 103 (Fig. 9), overlapping the edges of the key. Strips of this character cooperate with the other keys 98, 99 and 100, in order to retain them in their guides in the lower wall of frame 22.

Rod 89 is urged in a counterclockwise direction as viewed in Figs. 11 and 13, by the spiral spring 104. This spiral spring has its inner end anchored in a slot formed in the rod 89 and its outer end is anchored to the key 101. In the free position of the key 101, the extreme right hand fret 80 (Fig. 9) is urged into contact with the string 13, thereby determining the normal free length. The key 101 is limited in its motion toward the left as viewed in Fig. 11 as by the aid of a slot and pin stop mechanism similar to that described in connection with Fig. 12. In Fig. 11, the key 99 is illustrated and is shown as having a stop pin 105. Such a stop pin, however, is also carried by each of the other keys. The pin 105 operates in a slot 106 formed in the lower wall 23 of frame 22.

The upper portions of the keys are received immediately below the cover member 107. This cover member 107 is similar to cover member 44 heretofore described. The cover member 107 at its left hand edge is provided with a series of lips 108 extending downwardly to form a more complete cover.

The thumb of the right hand is adapted to cooperate with the head 109 of a lever 110. This lever 110 is shown in section in Fig. 11. It carries the spring fingers 111 cooperating to control the electrical circuits associated with the electrical pickups 112 cooperating with each of the strings 10, 11, 12 and 13 (Fig. 3). These pickups are likewise arranged to affect the operation of loud speaker 5; and they are shown as accommodated in the upper surface of table 1.

A recess 113 similar to recess 71 (Fig. 3) is indicated and disposed in the table 1 to provide a space for ready manipulation of the fingers of the right hand in conjunction with the keys 98, 99, 100 and 101, and the head 109. As before, the keys may carry graduation marks 114 that may cooperate with the upper edge 115 of cover 107, to indicate the angular positions of the corresponding rods 89.

The eight strings 6 to 13, inclusive, are each adapted to be set into vibration by vibratory mechanism operated by the lower extremities of the player. The mechanism for vibrating the strings of the first set 6, 7, 8 and 9, is substantially identical with the mechanism utilized for vibrating the strings of the second set of strings 10, 11, 12 and 13. The vibrator mechanism for

the first set is intended to be operated by the right foot and leg of the player; and the vibrator mechanism for the second set of strings is operated by the left foot and leg of the player.

5 Accordingly, a description of the mechanism associated with the right foot and leg of the player will serve as a description of the mechanism operated by the left foot and leg of the operator.

The mechanism utilized for vibrating the 10 strings involves a rod associated with each string and operating to strike the string with sufficient force to set it into vibration. The vibrator rod may be reciprocated at a rate determined by the operator so that the percussion effect is accomplished through any number of cycles.

15 The vibrator rods 116, 117, 118 and 119 associated with the strings 6, 7, 8 and 9 are illustrated in Figs. 3, 4, 5, 14, 15 and 16. The upper ends of the vibrator rods are formed conveniently of rectangular cross section and are guided by 20 the plates 121 fastened in the top of table 1.

The lower ends of the vibrator rods are shown as guided in a frame 122 (Figs. 4, 5, 14, 15 and 16).

25 This frame 122 comprises upper and lower bars, the lower one of which has guiding apertures for the flattened projecting ends 123, 124, 125 and 126. The manner in which the frame 122 is supported will be described hereinafter. It is sufficient for the present to note that the frame 122 serves to hold the vibrator rods 116, 117, 118 and 119 in appropriate spaced relationship.

30 Compression springs 127 are located between the upper and lower bars of the frame 122 and surround the vertical portions of the vibrator rods 119, etc. The upper ends of the compression springs abut against the lower surface of the upper portion of the frame. The lower ends of the compression springs cooperate with pins 40 128 passing through the flattened ends of the vibrator rods. Accordingly, these springs 127 urge the rods downwardly as viewed in Figs. 4 and 5, so that the upper ends of these vibrator rods are normally out of contact with their corresponding strings.

45 In order to urge the rods upwardly against the pressure of the springs 127 use is made of a rotary structure capable of being operated by the right foot of the player. This rotary structure

50 includes a hollow shaft 129 (Figs. 4, 5, 6, 14, 17, 18 and 19). It is rotatably supported at its right hand end by telescoping over a stationary cylindrical support 135 formed on a bracket 130. This bracket 130 is fastened appropriately to the end wall 131 of a housing 132 that encloses the vibrator rod mechanism. This housing in this instance is formed in conjunction with the side wall 2 and a bottom wall 133. The side wall 2 at its lower end carries a bearing bracket 134 (Figs. 2 and 4) serving as a bearing support for the left hand end of the shaft 129.

55 The shaft 129 carries a series of vibrator rod operators adapted to cooperate with the lower ends 123, 124, 125 and 126 of the vibrator rods.

60 These vibrator rod operators are in the form of wheels 136 to 145 inclusive. The two end wheels 136 and 145 have a broad face while the intermediate wheels are quite narrow. The specific axial spacing of these wheels, and the function 70 of such spacing will be explained hereinafter. Each of the wheels in the series is provided with a number of equally angularly spaced projections or cams 146 (see particularly Fig 5). These projections or cams when the shaft 129 is rotated 75 and when a wheel is in alignment with the lower

end of any of the vibrator rods will reciprocate the rods through a number of cycles, and thereby cause the corresponding strings to be vibrated.

Rotation of the shaft 129 in an oscillatory fashion or through complete revolutions may be accomplished by a smooth faced wheel 147 (Figs. 4 and 14). This wheel 147 may be provided with the sloping flanges 148 at its opposite ends to restrain the foot 149 (Fig. 2) of the player from sliding off axially with respect to the wheel. By operation of the foot 149 the wheel 147 may be rotated through a sufficient angle and at any desired speed so as to cause the vibrator to operate through repeated cycles.

The manner in which the wheel 147 is attached to the shaft 129 is best illustrated in Fig. 14. The wheel is hollow, being provided with one end web 149 and open at the opposite end. The wheel is also provided with a hollow hub 150 which telescopes over the left hand end of the shaft 129. The wheel 147 is attached to the shaft 129 as by the aid of the flat head bolt 151. If desired, a dowel pin 152 may be passed through the web 149 and into the end of the shaft 129 to maintain the wheel 147 in fixed angular position with respect to the shaft.

The flanges 148 provided at each end of the wheel 147 make it possible for the foot 149 of the player to exert an axial force with respect to the wheel 147. In this way the axial positions of wheels 136 to 145 inclusive may be adjusted so as to operate on any combination of the four vibrator rods. For example, in the position of Fig. 4, the wheel 147 and the shaft 129 are in their extreme right hand position. The only vibrator rod being operated in this position by rotation of shaft 128 is rod 118. This rod is being actuated by the wheel 144, all of the other wheels being inactive in this position, since they are not in alignment with any vibrator rods.

The shaft 129 may be moved axially toward the left to assume the position of Fig. 14. This movement is permitted since the hollow guiding shaft 135 extends for a considerable distance toward the left as seen in Fig. 14. In the position of Fig. 14, only the wheel 140 is active, causing vibrator rod 117 only to be operated. Further movement of the shaft 129 toward the left causes the wheels to assume the position of Fig. 16. In this position only wheel 136 is active and vibrator rod 116 alone is actuated when the wheel 147 is rotated.

Further axial movement toward the left as illustrated by the dot and dash position of Fig. 15 brings wheel 145 into position for operating only the vibrator rod 119.

Maximum axial movement of the shaft 129 toward the left is illustrated in the full line position of Fig. 15. In this case the hub of wheel 145 is in contact with the wall of the bearing bracket 134. In this position wheels 137 and 145 are both active and therefore both vibrator rods 117 and 119 are capable of being operated by rotation of wheel 147.

No attempt has been made to describe every possible axial position of the shaft 129. It may readily be demonstrated however, that with the axial spacings of the cam wheels as illustrated, it is possible to render any combination of the vibrator rods operable upon appropriate axial adjustment of the shaft 129.

In order to facilitate the axial adjustment of the shaft 129 to correspond to definite combination of vibrator rods that are to be operated, use is made of a mechanism most clearly illustrated

in Figs. 17 and 18. The shaft 129 carries a pair of hollow radial tubular members 153. The inner ends of these radial members communicate with the inside of the shaft 129. Sliding in these radial extensions is a cam follower mechanism including a roller 154. The roller 154 is journaled in the end of a slide 155 slidably in a radial direction within the hollow tubular members 153. In order to maintain the axes of both rollers 154 at right angles to the axis of the shaft 129, use is made of a pair of pins 156 extending outwardly from the slide 155 and engaging in elongated slots 157 formed on opposite sides of the tubular guides 153. Caps 158 close the outer ends of the tubular guides 153. Compression springs 159 urge the slides 155 radially inwardly. This inward movement is limited by the cam member 160 with which the rollers 154 cooperate. This cam member 160 is provided with diametrically opposite slots or keyways 161 and 162. The bottom of the slots is defined by concavities 163 corresponding with the convex periphery of the rollers 154 and spaced axially along the cam member 160. Since this cam member is fixed against axial movement, the axial adjustment of shaft 129 causes rollers 154 to move along the keyways 161, 162. Concavities 163 serve to position the shaft 129 in an axial direction; and the rollers 154 must come to rest within a concavity. In this way the axial adjustment of the vibrator operating mechanism is accomplished in a step by-step manner. Each step corresponds to a definite combination of wheels that cooperate with the vibrator rods. Accordingly, the selection of the combination of rods to be operated is dependent upon the position of the rollers 154 with respect to the cam member 160.

Since the rollers 154 serve to key the shaft 129 and the cam member 160 together, the cam member 160 must be permitted to rotate along with the shaft 129. For this purpose the cam member 160 is mounted for rotation upon a stationary shaft 164. This shaft 164 has a reduced end 165 passing through a bushing 166. This bushing 166 is fastened within the left hand end of the guide bearing 135. The right hand end of extension 165 is threaded for the accommodation of a nut 167. Slot 168 in the end of extension 165 is provided for the accommodation of a screw driver, for making it possible conveniently to adjust the angular position of the cam member.

Without any further precautions, axial movement of the shaft 129 may be prevented by interference between some of the cam teeth 146 (Fig. 4), carried by the actuator wheels 135 to 145 inclusive, with the lower ends of the vibrator rods. In order to ensure against this occurrence, the arrangement is such that when the foot 149 is not acting to rotate the shaft 129, the shaft 129 comes to rest in an angular position where such interference can not occur.

For this purpose the left hand end of cam member 160 is provided with a series of teeth 169 (Fig. 20). These teeth or serrations are adapted to cooperate with the corresponding teeth or serrations 170 in the end of a collar 171. This collar 171 is slidable on the stationary shaft 164. It is restrained against angular movement by the aid of a pin 172 passing through appropriate slots in the hub of the collar 171. A compression spring 173, mounted on the left hand end of the shaft 164, constantly urges the collar 171 toward the right as viewed in Fig. 17.

The serrations or teeth 169, 170, have sides sloping to such an extent that the cam member

#63 can assume an angular position of rest only in a position where these serrations engage completely. As illustrated in Fig. 20, the serrations are angularly spaced to correspond to the spaces between the cams or projections 143 carried by the wheels 136 to 145 inclusive.

As heretofore stated, the cycles of operation of the vibrator rods 116, 117, 118 and 119 have periods corresponding to the rate at which shaft 129 is angularly moved by the foot of the player. When the axial position of the shaft 129 is such that more than one of the vibrator rods 116, etc. is operated, it is advantageous sometimes to arrange matters in such a way that the cycle of operations of one vibrator rod be out of phase with the cycle of operations of another rod. For example, it may be desirable that, as wheel 147 (Fig. 15) is rotated by the foot, the vibrator rod 117 may be moved upwardly ahead of the time when vibrator rod 119 is moved upwardly. In other words, the forces placing the strings into vibration come into action in succession, rather than simultaneously.

In order to effect this result, the frame 122 is mounted for slight angular adjustment about a vertical pivot. Thus as shown in Fig. 4, the frame 122 is provided at its right hand end with stub shafts 174 and 175. These stub shafts are mounted in appropriately formed bearings supported on the bracket 130. At the left hand end of the frame 122 (Fig. 6) a recess 176 is formed in which operates the ball ended arm 177. This arm 177 is angularly adjustable, since it is mounted on a long shaft 178 extending vertically upwardly of the mechanism.

The lower end of shaft 178 is pivoted by the aid of bracket 134. The upper end is pivoted in a bracket 179 (Fig. 4). As the shaft 178 is adjusted angularly, the angular position of the frame 122 is also adjusted angularly. One extreme position is illustrated in Fig. 6. This position corresponds to the one that the apparatus assumes normally, under the influence of a torsion spring 179 (Fig. 4). This torsion spring is coiled around the shaft 178. One end of the spring is attached to the wall 2. The other end of the spring is attached to the hub 180 of an arm 181 (Figs. 4 and 7). Thus, hub 180 is fastened to the shaft 178. The arm 181 carries an adjustable abutment 182 adapted to cooperate with the surface of wall 2. The tension of the spring 179 is such that it creates a torque tending to rotate shaft 178 in clockwise direction, as viewed in Fig. 7. It is, however, restrained against further movement than as illustrated in Fig. 7, by contact of the adjustable abutment 182 with the right hand surface of the wall 2.

By angular adjustment of the frame 122 therefore, the ends 123 to 126 of the vibrator rods fall along a line that is non-parallel with the axis of the shaft 129. As seen most clearly in Fig. 5, this has the effect of angular displacement of these ends about the axis of shaft 129, and a corresponding phase displacement of the operation of the corresponding vibrator rods.

In order to be sure that there be no binding of the rods in the guides, the guide apertures in the lower part of frame 122 are formed with convex sides as clearly indicated in Fig. 5. The upper sides of the frame 122 are provided with through apertures that have clearance sufficiently great to prevent binding. The slight angular motion of the frame 122 has no material effect upon the guides disposed at the upper ends of the vibrator rods.

Angular adjustment of shaft 178 is intended to be performed by the knee 183 (Fig. 2) of the player. The knee is arranged to press against a side lever 184 (Figs. 2, 4 and 7) formed conveniently of sheet metal. The inner end of the lever 184 is turned to form a hub by the aid of which it may be attached to the shaft 178. The wall 2 is appropriately apertured as indicated at 185 to permit the lever 184 to extend through to the left hand side of the wall 2. If desired, an arcuate guard extension 186 may be provided for the lever 184.

The description of the apparatus for selectively vibrating the strings 6, 7, 8 and 9 is now complete. A substantially similar structure can be arranged to be operated by the left foot of the player, for operating the vibrator rods 187, 188, 189 and 190 (Fig. 3). These vibrator rods co-operate with the left hand ends of the strings 10, 11, 12 and 13.

In the operation of the instrument the player is seated in a convenient position so that he may rest his feet upon the wheels 147. Then by appropriate movement of the knee and the foot he can select and operate the vibrator rods as desired. At the same time he utilizes his right and left hands respectively for manipulating the keys 40', 41, 42, 43 at one end of the instrument, and the keys 98, 99, 100 and 101 at the other end of the instrument. The thumbs of the hands may be utilized as desired for controlling the electrical circuits associated with the electrical pick-ups.

The inventor claims:

- 35 1. In a musical instrument, one or more tensioned strings, and means for vibrating said string or strings, comprising a rotary member, one or more string engaging rods operated by rotation of said member, means guiding the movement of the rods in a substantially longitudinal direction, and means for shifting said rotary member to various positions to selectively determine the rods operated thereby during its rotation.
- 40 2. In a musical instrument, one or more tensioned strings, and means for vibrating said string or strings, comprising one or more linearly movable rods adapted to engage the strings, manual means for operating said rods, and means mounting said manual means for transverse movement across said rods to selectively determine the rods operated thereby.
- 45 3. In a musical instrument, one or more tensioned strings, and means for vibrating said string or strings, comprising a manually controlled wheel having angularly spaced projections, one or more linearly movable rods, respectively for each string, operated by angular motion of the projections to move into and out of contact with the respective string, and means for shifting said wheel to selectively determine the rod or rods operable by its projections.
- 50 4. In a musical instrument, a plurality of tensioned strings, a plurality of string vibrators respectively associated with said strings, manually controlled means engageable with said strings at various points along their normally unsupported lengths for determining the free length of said string, and manually controlled means for selectively operating any one or more said vibrators.
- 55 5. In a musical instrument, a plurality of tensioned strings, a plurality of string vibrators respectively associated with said strings, manually controlled means determining the free length of any string, and means for selectively operating

any one or more of said vibrators, comprising a rotary structure, having axially spaced means for operating said vibrators, and means independent of the rotation of said structure, for adjusting the structure axially.

6. In a musical instrument, a plurality of tensioned strings, a plurality of string vibrators respectively associated with said strings, manually controlled means engageable with said strings at various points along their normally unsupported lengths for determining the free length of any string, and means for selectively operating any one or more of said vibrators, comprising an angularly and axially adjustable structure, having axially spaced means for operating said vibrators, and means limiting and maintaining the adjusted axial positions of said structure.

7. In a musical instrument, a plurality of tensioned strings, vibrators respectively cooperating with the strings, and manually controlled means for operating said vibrators, comprising a rotary structure having a series of axially spaced members, each of said members having angularly spaced projections cooperating to move said vibrators alternately to contact and release the corresponding strings, and independently operable means for axially adjusting said rotary structure for selectively alining the members with said vibrators.

8. In a musical instrument, a plurality of tensioned strings, vibrators respectively cooperating with the strings, and means for operating said vibrators, comprising a rotary structure having a series of axially spaced members, each of said members having angularly spaced projections cooperating to move said vibrators alternately to contact and release the corresponding strings, means for axially adjusting said rotary structure for selectively alining the members with said vibrators, and means determining and maintaining the adjusted axial positions of said structure.

9. In a musical instrument, a plurality of tensioned strings, vibrators respectively cooperating with the strings, and manually controlled means for operating said vibrators, comprising a rotary structure having a series of axially spaced members, each of said members having angularly spaced projections cooperating to move said vibrators alternately to contact and release the corresponding strings, means for axially adjusting said rotary structure for selectively alining the members with said vibrators, and means ensuring that said rotary structure assumes definite angular positions between periods of rotation.

10. In a musical instrument, a plurality of tensioned strings, manual means engageable with said strings at various points along their normally unsupported lengths for adjusting the free lengths of said strings, vibrators respectively cooperating with said strings, and means capable of operation by the lower extremity, for operating said vibrators, comprising a rotary structure having angularly spaced projections cooperating to move said vibrators alternately to contact and release the corresponding strings.

11. In a musical instrument, a plurality of tensioned strings, manual means for adjusting the free lengths of said strings, vibrators respectively cooperating with said strings, and means capable of operation by the lower extremity, for operating said vibrators, comprising a rotary structure having a series of axially spaced members, each of said members having angularly spaced pro-

jections cooperating to move said vibrators alternately to contact and release the corresponding strings, and means for axially adjusting said rotary structure by a force exerted by a lower extremity, for selectively alining the members with said vibrators.

12. In a musical instrument, a plurality of tensioned strings, a plurality of vibrators adapted respectively to vibrate said strings, a mechanism for selectively operating any one or more of said vibrators, alternately to contact and release the corresponding strings, and means for adjusting between limits, the relative phase relationship of the cycles of operations of the selected vibrators, whereby the respective strings are not contacted simultaneously, but at spaced intervals.

13. In a musical instrument, a plurality of tensioned strings, a plurality of vibrators adapted respectively to vibrate said strings, a rotary structure for operating said vibrators, said structure having axially spaced members, each member having a series of angularly spaced projections adapted to cooperate with a respective vibrator, and means for adjusting the phase relation between the respective cycles of operation of the vibrators, comprising a frame guide for the vibrators, and means for angularly adjusting the guide about an axis transverse to the axis of rotation of the structure.

14. In a stringed musical instrument, a plurality of substantially parallel tensioned strings, means operable from one end of the series of strings for adjusting the free length of some of the strings, and means operable from the other end of the series of strings for adjusting the free length of the other strings, both of said means comprising respective instrumentalities engageable with each of said strings at various selected positions along its length for selectively determining the rate of vibration of said string.

15. In a stringed musical instrument, a pair of sets of substantially parallel tensioned strings, the strings of one set alternating with those of the other set, means operable from one end of the first set for adjusting the free length of the strings in said first set, said means being selectively engageable with each string in said first set at various points along its length for selectively determining its vibration rate, and means operable from the corresponding end of the second set for adjusting the free length of the strings in said second set, said last mentioned means being selectively engageable with each string in said second set at various points along its length for selectively determining its vibration rate.

16. In a stringed musical instrument, a plurality of substantially parallel tensioned strings, means operable from one end of the series of strings for adjusting the free length of some of the strings, means operable from the other end of the series of strings for adjusting the free length of the other strings, both of said means comprising respective instrumentalities engageable with each of said strings at various selected points along its length for selectively altering the rate of vibration of said string, and manual means for selectively vibrating said strings.

17. In a stringed musical instrument, a pair of sets of substantially parallel tensioned strings, the strings of one set alternating with those of the other set, means operable from one end of the first set for adjusting the free length of the strings in said first set, said means being selectively engageable with each string in said first

set at various points along its unsupported length for selectively determining its vibration rate, means operable from the corresponding end of the second set for adjusting the free length of the strings in said second set, said last-mentioned means being selectively engageable with each string in said second set at various points along its unsupported length for selectively determining its vibration rate, and manual means for selectively vibrating said strings.

18. In a stringed musical instrument, a plurality of substantially parallel tensioned strings, means operable from one end of the series of strings for adjusting the free length of some of the strings, means operable from the other end of the series of strings for adjusting the free length of the other strings, both of said means comprising respective instrumentalities engageable with each of said strings at various selected positions along its length for selectively determining the rate of vibration of said string and mechanism adapted to be rotated by the lower extremities, for selectively vibrating said strings.

19. In a stringed musical instrument, a plurality of substantially parallel tensioned strings, means operable from one end of the series of strings for adjusting the free length of some of the strings, means operable from the other end of the series of strings for adjusting the free length of the other strings, both of said means comprising respective instrumentalities engageable with each of said strings at various selected positions along its length for selectively determining the rate of vibration of said string and a pair of rotary structures, adapted to be rotated respectively by the lower extremities of the player for selectively vibrating the strings by alternately contacting and releasing the strings, through one or more cycles.

20. In a stringed musical instrument, a plurality of substantially parallel tensioned strings, means operable from one end of the series of strings, for adjusting the free length of some of the strings, means operable from the other end of the series of strings for adjusting the free length of the other strings, and a pair of rotary structures, adapted to be rotated respectively by the lower extremities of the player for selectively vibrating the strings by alternately contacting and releasing the strings, through one or more cycles, and means also operated by the lower extremities, for adjusting the relative phase relation between the cycles of the respective strings, whereby the respective strings are not contacted simultaneously, but at spaced intervals.

21. In a stringed musical instrument, a plurality of substantially parallel tensioned strings, means operable from one end of the series of strings for adjusting the free length of some of the strings, means operable from the other end of the series of strings for adjusting the free length of the other strings, and a pair of rotary structures, adapted to be rotated respectively by the lower extremities of the player, for selectively vibrating the strings, said rotary structures being axially adjustable by aid of the lower extremities, for determining the string or strings to be vibrated.

22. In a musical instrument, a plurality of tensioned strings, and means for vibrating said strings, comprising a plurality of string contacting members, operators for respectively vibrating said members, each of said operators having uniformly spaced portions adapted in succession to move said members, and manual means for moving said operators to positions permitting said operators to vibrate one or more of said members or to prevent said operators from vibrating one or more of said members.

23. In a stringed musical instrument, a support, a plurality of tensioned strings supported by the aid of said support, manually operated means for adjusting the free vibrating lengths of a number of said strings, and operable adjacent one end of the support, and manually operated means for adjusting the free vibrating lengths of other strings, and operable adjacent the other end of said support, both of said means comprising respective instrumentalities engageable with each of said strings at various selected positions along its length for selectively determining the rate of vibration of said string.

24. In a musical instrument, one or more tensioned strings, and means for vibrating said string or strings, comprising a rotary member, one or more string engaging rods operated by rotation of said member, means guiding the movement of the rods in a substantially longitudinal direction, and means for axially shifting said rotary member transversely of said rods to various positions to selectively determine the rods operated thereby.

25. In a musical instrument, a plurality of strings, means supporting each of said strings at spaced points in tensioned condition, a plurality of string vibrators respectively associated with said strings, manually controlled means selectively engageable with each of said strings at various points intermediate its supporting points to determine the free length of said string, and manually controlled means for selectively operating any one or more of said vibrators.

26. In a musical instrument, a plurality of tensioned strings, a plurality of string vibrators respectively associated with said strings, manually controlled means determining the free length of any string, means for selectively operating any one or more of said vibrators, comprising a rotary structure having axially spaced means for operating said vibrators, and means for adjusting the structure axially to variously position said axially spaced means and correspondingly vary the one or more vibrators operated thereby during rotation of said structure.
